CLAIM

The ornamental design for a cleaner case, as shown and described.

DESCRIPTION

FIG. 1 is a top, front, right side perspective view of a cleaner case, shown in an open position showing our new design;

FIG. 2 is a bottom, rear, left side perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a right side elevational view thereof, the left side elevational view being a mirror image;

FIG. 8 is a top, front, right side perspective view of the cleaner case shown in a closed position;

FIG. 9 is a bottom, rear, left side elevational view thereof;

FIG. 10 is a top plan view thereof;

FIG. 11 is a bottom plan view thereof;

FIG. 12 is a front elevational view thereof;

FIG. 13 is a rear elevational view thereof; and,

FIG. 14 is a right side elevational view thereof, the left side elevational view being a mirror image.
